Ira L. Nickerson

UNITED STATES PATENT OFFICE.

EDWARD W. STEVENS, OF DETROIT, MICHIGAN, ASSIGNOR TO CHICAGO PNEUMATIC TOOL COMPANY, OF NEW YORK, N. Y., A CORPORATION OF NEW JERSEY.

TOOL RETAINER.

Application filed December 17, 1924. Serial No. 756,388.

This invention relates to retaining devices for the working tool of percussive machines, such for example as pneumatic hammers. More particularly it relates to devices of this character adapted for quick application to and removal from such machines in order to facilitate the interchange of working tools. This invention is in the nature of an improvement on or further development of a prior invention disclosed in my copending application Serial No. 652,369 filed July 18, 1923, for quick acting tool retainer.

The so-called quick acting retainers such as disclosed in my copending application above noted are quickly released from the percussive machine by a rotative movement of the retainer. As the operator of such a machine ordinarily grasps the retainer with one hand while the other is used on the throttle or switch handle of the machine, it has been found in practice that the operator at times unconsciously twists the retainer relative to the machine, thus releasing both the retainer and the working tool, which may be projected from the machine by the next impact of the percussive element and injure some one or damage the work.

One object of the invention is to prevent inadvertent release of the retainer in the manner described. Another object is securely to lock the retainer in operative position against accidental release but to arrange for quickly unlocking it when its release is intentional and desired.

In order to illustrate the invention one concrete embodiment thereof is shown in the accompanying drawings, in which:

Figure 1 is a side elevational view of a pneumatic hammer equipped with the invention.

Figure 2 is an enlarged transverse sectional view substantially on line 2-2 of Figure 1.

Figure 3 is a longitudinal vertical sectional view on an enlarged scale of the front end of the hammer shown in Figure 1 taken on line 3-3 of Figure 2.

Fig. 4 is a fragmentary longitudinal sectional view on the line 4-4 of Fig. 2.

The embodiment of the invention chosen for the purpose of illustration consists of a retainer 4 in the form of a sleeve adapted to be telescoped over the cylinder *a* of a per-

cussive machine such as the pneumatic hammer A shown in Figure 1. This retainer is for the purpose of maintaining in operative position the working tool B which is acted upon by the piston of the pneumatic hammer A or other percussive machine. This working tool may be of any type required by the work to be performed such as a button set, chisel, drill steel, punch, etc. In the present instance the working tool shown is a chisel B held within the retainer 4 by the outer inturned flange or lip 5 of the latter, the chisel being guided in the end of the cylinder *a* by a bushing *b* which is held in spaced relation to the flange 5 by rubber buffer *b'*.

The retainer 4 is held on the cylinder *a* against axial withdrawal by opposed latching blocks 6 normally forced through openings 7 in the sleeve by an arcuate spring 8 seated in a groove defined by spaced circumferential flanges 9 on the sleeve, the blocks being secured to the spring in any suitable manner as by rivets 10. The latching blocks 6 are arranged to seat in transverse cuts or grooves *a'* in the hammer cylinder, said grooves providing stop shoulders *a''* engaged by blocks 6. As will be clear from Fig. 2 rotation of the sleeve retainer 4 in either direction relative to cylinder *a* will force the latching blocks 6 out of grooves *a'* and permit the retainer to be withdrawn from the cylinder whenever desired. The structure so far described conforms substantially to that of my copending application above referred to.

In order to prevent accidental rotation of the retainer sleeve and its consequent release suitable means, comprising the present invention, are provided for locking the sleeve in such position that the latching blocks 6 register with and remain in the cylinder grooves *a'*. This locking means preferably takes the form of member 11 (Fig. 2) on the sleeve normally engaging a recess *a''* in cylinder *a*. Member 11 is preferably spring pressed to cause it to remain in operative position in recess *a''*. For simplicity and ease of manufacture and assembly it may be in the form of the bent end of a spring ring 12 seated in a circumferential groove 13 in sleeve 4, the end 11 being arranged to extend through an opening 14 in the sleeve. In practice it is preferable to provide the

2

cylinder *a* with two recesses *a*³ properly disposed relative to the grooves *a'* so that the retainer sleeve 4 may be conveniently applied to the cylinder *a* in any position in 5 which the blocks 6 will register with the grooves *a'*. Further and by preference the recesses *a*³ are formed as axial grooves and the latching blocks 6 are formed with rearward bevelled surfaces, so that the retainer 10 4 with the working tool B therein is readily applied to the hammer cylinder by aligning the locking member 11 with one of the axial grooves *a*³ and then driving the retainer into telescoping relation with the cylinder *a* 15 by a forceful push or blow. To permit the removal of the retainer for changing the working tool or for any other reason an axial groove 15 (Figures 1 and 2) intersecting circumferential groove 13 adjacent 20 opening 14 is provided on the retainer sleeve 4 for the insertion beneath locking ring 12 of a pointed instrument such as a nail indicated at X (Fig. 2) to be used as a lever to pry up the inturned end 11 or locking member 25 and remove it from engagement with the locking groove *a*³ as indicated in the broken line position of the parts in Fig. 2. The retainer sleeve 4 can then be rotated to cam the latching blocks 6 out of their grooves *a'* 30 whereupon the retainer is readily removed from the hammer cylinder.

While but one form of the invention has been herein disclosed it is to be understood that the present invention is not restricted 35 to the specific details thereof but covers all modifications and adaptations within the spirit of the invention and within the scope of the appended claims.

I claim as my invention:

40 1. The combination with a percussive machine and a working tool therefor of retaining means for said tool comprising a sleeve having latching means for retaining it in operative position on the machine, said 45 latching means being releasable by rotation of said sleeve, and means on said sleeve operating automatically on application of said sleeve for positively locking said sleeve against rotation.

50 2. The combination with a percussive machine and a working tool therefor of retaining means for said tool comprising a sleeve having latching means for retaining it in operative position on the machine, said 55 latching means being releasable by rotation of said sleeve, and a retractable member co-operating with a recess in said machine and operating automatically on application of said sleeve to said machine for positively 60 locking said sleeve against accidental rotation.

65 3. The combination with a percussive machine and a working tool therefor of retaining means for said tool comprising a sleeve having latching means for retaining

it in operative position on the machine, said latching means being releasable by rotation of said sleeve, and a spring-pressed member normally engaging an axial groove in said machine beneath said sleeve to permit easy 70 application of said sleeve and for preventing accidental rotation of said sleeve.

4. The combination with a percussive machine and a working tool therefor of retaining means for said tool comprising a 75 sleeve having latching means for retaining it in operative position on the machine, said latching means being releasable by rotation of said sleeve, a locking member arranged to permit easy application of said sleeve and 80 to engage an axial recess in said machine to prevent accidental rotation of said sleeve when applied, and a spring ring encircling said sleeve for maintaining said member in locking position.

85 5. The combination with a percussive machine and a working tool therefor of retaining means for said tool comprising a sleeve having latching means for retaining it in operative position on the machine, said 90 latching means being releasable by rotation of said sleeve, and a spring ring encircling said sleeve with one end projecting inwardly through an opening in said sleeve to engage an axial recess in said machine, thereby to 95 permit instant application of said sleeve and releasably to lock said sleeve against accidental rotation.

6. The combination with the cylinder of a 100 pneumatic hammer, said cylinder having a groove providing a stop shoulder, of means for detachably retaining a working tool in operative relation therewith comprising a sleeve engaging the cylinder and having a latching member adapted to seat in said 105 groove and engage said stop shoulder, said member being arranged to be forced out of said groove to release said sleeve on rotation of the latter on said cylinder, and locking means for positively preventing such rotative movement of said sleeve automatically 110 operable on applying said sleeve to said cylinder.

7. The combination with the cylinder of 115 a pneumatic hammer, said cylinder having grooves providing stop shoulders, of means for detachably retaining a working tool in operative relation therewith comprising a sleeve engaging the cylinder and having 120 latching members adapted to seat in said grooves and engage said stop shoulders, said members being arranged to be forced out of said grooves to release said sleeve on rotation of the latter on said cylinder, and a retractable locking member on said sleeve 125 automatically engaging a recess in said cylinder on application of said sleeve thereto positively to prevent rotative movement of said sleeve.

8. The combination with the cylinder of a 130

- 6 pneumatic hammer, said cylinder having grooves providing stop shoulders, of means for detachably retaining a working tool in operative relation therewith comprising a sleeve engaging the cylinder and having spring pressed latching members adapted to seat in said grooves and engage said stop shoulders, said members being forced out of said grooves to release said sleeve on 10 rotation of the latter on said cylinder, and a locking member projecting through an opening in said sleeve automatically to engage an axial groove in said cylinder on application of said sleeve to said cylinder 15 thereby positively to prevent accidental rotative movement of said sleeve but to facilitate the mounting of said sleeve on said cylinder.
- 7 9. The combination with the cylinder of a pneumatic hammer, said cylinder having grooves providing stop shoulders, of means for detachably retaining a working tool in operative relation therewith comprising a sleeve engaging the cylinder and having spring pressed latching members adapted to seat in said grooves and engage said stop shoulders, said members being forced out of said grooves to release said sleeve on rotation of the latter on said cylinder, and a locking member extending through an opening in said sleeve and automatically engaging an axial recess in said cylinder on application of said sleeve thereto for preventing 25 accidental rotation of said sleeve, and a spring ring encircling said sleeve for yieldingly holding said locking member in operative position.
- 8 10. The combination with the cylinder of a pneumatic hammer, said cylinder having transverse grooves providing stop shoulders and axial grooves in a definite relation to said transverse grooves, of means for detachably retaining a working tool in operative 30 relation therewith comprising a sleeve engaging the cylinder and having a circumferential groove, a spring seated in said groove, latching blocks carried by said spring extending through openings in said sleeve to seat in said transverse cylinder grooves and engage said stop shoulders, said blocks being forced out of said grooves to release said sleeve on rotation of the latter on said cylinder, a spring ring encircling said sleeve and carrying a locking member which extends through an opening in said sleeve automatically to engage one of said axial grooves of said cylinder on application of said sleeve thereto thereby to lock said sleeve against accidental rotation movements, and means adjacent said spring ring to permit the insertion of an instrument for lifting said locking member to unlock said sleeve.
- 9 11. A tool retaining device for use with percussive machines comprising a sleeve of a size to pass over the cylinder of the percussive machine, means on said sleeve for cooperation with grooves in said cylinder to prevent axial withdrawal of said sleeve, said means being arranged to be released on rotative movement of said sleeve, and means 40 for cooperation with a recess in said cylinder automatically and positively to lock said sleeve against rotation.
- 10 12. A tool retaining device for use with percussive machines comprising a sleeve of a size to pass over the cylinder of the percussive machine, means on said sleeve for cooperation with grooves in said cylinder to prevent axial withdrawal of said sleeve, said means being arranged to be released on rotative movement of said sleeve, and a retractable member arranged automatically to engage a recess in said cylinder on application of the sleeve thereto positively to lock 45 said sleeve against accidental rotative movement.
- 11 13. A tool retaining device for use with percussive machines comprising a sleeve of a size to pass over the cylinder of the percussive machine, means on said sleeve for cooperation with grooves in said cylinder to prevent axial withdrawal of said sleeve, said means being arranged to be released on rotative movement of said sleeve, and a spring-pressed member arranged automatically to engage an axial groove in said cylinder positively to prevent accidental rotation of said sleeve.
- 12 14. A tool retaining device for use with percussive machines comprising a sleeve of a size to pass over the cylinder of the percussive machine, a spring pressed latching block on said sleeve for cooperation with a groove in said cylinder to prevent axial withdrawal of said sleeve, said block being released on rotative movement of said sleeve on said cylinder, and a spring pressed locking member projecting through an opening in said sleeve automatically to engage an axial recess in said cylinder positively to prevent accidental rotative movement of said sleeve.
- 13 15. A tool retaining device for use with percussive machines comprising a sleeve of a size to pass over the cylinder of the percussive machine, spring pressed latching blocks on said sleeve for cooperation with shoulders on said cylinder to prevent axial withdrawal of said sleeve in at least one position of the latter on said cylinder, and a spring ring encircling said sleeve with one end projecting inwardly through an opening therein automatically to engage an axial recess in said cylinder on application of the sleeve thereto thereby to retain said sleeve in said position.
- 14 16. A tool retaining device for use with percussive machines comprising a sleeve of a size to pass over the cylinder of the percussive machine, spring pressed latching

blocks on said sleeve for cooperation with shoulders on said cylinder to prevent axial withdrawal of said sleeve in at least one position of the latter on said cylinder, a 5 spring ring encircling said sleeve with one end projecting inwardly through an opening therein automatically to engage an axial recess in said cylinder thereby to retain said

sleeve in said position, and means providing for the lifting of said ring to prevent rotation of said sleeve and its release from said cylinder. ¹⁰

Signed by me at Detroit, Michigan this 5th day of December, 1924.
